FIG.1.

FIG.2.

FIG.3.

FIG.4.

FIG. 1 is a perspective view of a toothbrush handle, showing my new design;

FIG. 2 is an elevational view of one side thereof, the opposite side being a mirror image thereof;

FIG. 3 is a bottom plan view thereof;

FIG. 4 is a top plan view thereof.

The broken line disclosure of an outline of toothbrush bristles in FIGS. 1-3 is for illustrative purposes only and forms no part of the claimed design.

I claim:

The ornamental design for a toothbrush handle, as shown and described.
